UNITED STATES PATENT OFFICE.

THOMAS A. HOOVER, OF FRESNO, CALIFORNIA, ASSIGNOR TO HOOVER AUXILIARY SPRING COMPANY, OF SAN FRANCISCO, CALIFORNIA, A CORPORATION OF CALIFORNIA.

VEHICLE-SPRING.

1,114,359.

Specification of Letters Patent. Patented Oct. 20, 1914.

Application filed November 6, 1911. Serial No. 658,778.

To all whom it may concern:

Be it known that I, THOMAS A. HOOVER, a citizen of the United States, residing at Fresno, in the county of Fresno and State 5 of California, have invented certain new and useful Improvements in Vehicle-Springs, of which the following is a specification, reference being had to the accompanying drawings.

10 This invention relates to improvements in vehicle springs and particularly to improvements in vehicle springs of that general type called elliptic springs; and an object of this invention is to provide means 15 for supporting the main spring during both its downward and upward movements and in limiting the same.

Another object of this invention is to provide an elliptic spring with simple and efficient means for absorbing the recoil and preventing shocks and jolts due, for example, to inequalities in the roadway.

20 A third object of this invention is the provision of means for strengthening an elliptic spring to resist excessive deformation under an overload without in any degree impairing the resilient qualities of the 25 same under normal and light loads.

Other features of this invention will be 30 pointed out hereinafter in the description and claims.

In the drawings illustrating the principle 35 of this invention and the best mode now known to me of applying that principle, Figure 1 is a side elevation of my new vehicle spring; Fig. 2 is a similar view but shows the position assumed by the parts 40 during recoil or rebound; and Fig. 3 is a detail showing in elevation an end of a modified form of my new spring.

The main semi-elliptic spring *a* is made up of a series of leaves *b* each shorter than the one which overlies it, as is usual in this type of vehicle spring. One end of the 45 main semi-elliptic spring *a* is pivotally connected at one end with the chassis or frame member *c*, while its other end is connected therewith by means of a link *d*. Beneath the semi-elliptic spring there is arranged 50 an auxiliary spring *e*, after the manner illustrated and described in the patent granted me August 13, 1907, No. 862,917.

As is shown and described in that patent, the main and auxiliary springs are connected together by a centrally-disposed bolt 55

f and by means of U-shaped clips *g* the ends of which are anchored in the block *h*, in which is carried the axle end *i*.

Above the main spring *a* there is arranged a recoil spring which may be a single 60 spring but which is preferably two-part, as shown. The parts *j* of this recoil spring are identical in construction and are preferably built up of a plurality of leaves, although each may comprise only a single 65 leaf. Near the center of each recoil spring *j* there is fastened a hanger-block *k*, in which is pivotally fastened the upper ends of a pair of links *m* the lower ends of which are pivotally fastened to an end of one of 70 the leaves of the auxiliary spring *e*. The outer end of each part *j* of the recoil spring is forked and is connected by passing a bolt *n* through this forked end and an eye formed on one of the leaves of the main 75 spring *a*. Just above the center of the main spring there is fastened to the chassis or frame member *c* the upper ends of a pair of bracket plates or hanger plates *o* the lower ends of which carry a shaft *p* on which is 80 mounted a cylindrical block *q*. The latter is preferably of rubber or like resilient material. The inner opposed ends of the parts *j* of the recoil spring are formed with eyes *r* through which is looped a strap *s*, which 85 may be of leather or other suitable material. This strap passes over the cylindrical block *q*, as shown.

As explained in the patent above-referred to, the auxiliary spring *e* serves to support 90 and strengthen the main spring *a*, when an excessive load or overload is thrown thereon and furnishes a yielding base which resists the deflecting force at that time, supports the main spring and prevents pivotal strain 95 at the base thereof. The deflection of the main spring is gradually lessened, the extent of its downward stroke is shortened, efficient support is given when support is most needed and a violent rebound is in a measure prevented by this auxiliary spring. During recoil or rebound, the auxiliary spring *e* supports the recoil spring *j* and prevents violent jolts or shocks which might otherwise occur. The action of the recoil spring *j* in limiting the upward movement of the chassis *c* will be obvious from a study of Fig. 2 without further description. In the modified form shown in Fig. 3, the top leaf of the recoil spring *j'* is connected to 100 105 110

the upper ends of the links *m* and the block *k* is dispensed with.

I claim:

1. A vehicle spring comprising a main spring; a recoil spring fastened thereto at its outer end and free at its inner end; an auxiliary spring; and a device which fastens the inner end of said recoil spring to said auxiliary spring and transmits the vibrations of one to the other thereof; said main spring being interposed between said recoil and auxiliary springs.

2. A vehicle spring comprising a main spring; a recoil spring fastened thereto at its outer end and free at its inner end; an auxiliary spring free at its outer end and fastened to said main spring near the center thereof; and a device which fastens the free ends of said recoil and auxiliary spring together and transmits the vibrations of one to the other thereof; said main spring being interposed between said recoil and auxiliary springs.

3. A vehicle spring having an auxiliary spring; a two-part recoil spring the inner opposed ends of the parts of which are connected with said auxiliary spring; and a main spring interposed between said springs.

4. A vehicle spring having an auxiliary spring; a two-part recoil spring the inner opposed ends of the parts of which are connected with said auxiliary spring; and a main spring interposed between said springs and connected with the outer ends of the parts of said recoil spring.

5. A vehicle spring comprising a main spring; a flat recoil spring fastened thereto at its outer end and extending lengthwise of said main spring and having its inner end free; and a flexible suspensory device which is connected to the free end of said recoil spring and is adapted to suspend the same from the vehicle frame.

6. A vehicle spring having a main spring; a flat two-part recoil spring carried thereby and having its inner opposed ends free to yield; and a flexible suspensory device which is connected to the last-named ends and is adapted to suspend the same from the vehicle frame.

7. A vehicle spring having a main spring; a flat two-part recoil spring extending lengthwise thereof and fastened at its outer ends thereto; and a sling which connects the inner opposed free ends of said recoil spring and is adapted to suspend the same from the vehicle frame.

8. A vehicle spring having a main spring;

a flat two-part recoil spring extending lengthwise thereof and fastened at its outer ends thereto; and a slidale suspensory device looped through the free inner opposed ends of said recoil spring, and adapted to sling the same upon the vehicle frame.

9. The combination with a vehicle having a main spring; a flat two-part recoil spring extending lengthwise thereof and fastened at its outer ends thereto; and a sling which connects the free inner opposed ends of said recoil spring; of a support over which said sling is free to slide.

10. The combination with a vehicle spring having a main spring; a flat two-part recoil spring which extends lengthwise thereof; and a suspensory device looped through the free inner opposed ends of the parts of the latter; of a support over which said suspensory device is free to slide.

11. The combination with a vehicle spring having a main spring; a flat two-part recoil spring which extends lengthwise thereof; and a sling which connects the free inner opposed ends of said recoil spring; of a support from which said sling is hung.

12. A vehicle spring having a main spring; a recoil spring extending lengthwise thereof and having its outer end fastened thereto; and yielding means carried by said main spring and having its outer end free and connected with the free inner end of said recoil spring.

13. A vehicle spring having a main spring; a two-part recoil spring extending lengthwise thereof and having its outer ends fastened thereto; and yielding means carried by said main spring and having its free outer ends connected to the free opposed inner ends of said recoil spring.

14. A vehicle spring having a main spring; a two-part recoil spring extending lengthwise thereof and having its outer end fastened thereto; and yielding means carried by said main spring and having its free outer ends connected to the free opposed inner ends of said recoil spring; in combination with a flexible suspensory device connected to the last-named ends and adapted to suspend the same from the vehicle frame.

Signed at Fresno, California, this 25th day of October in the presence of the two undersigned witnesses.

THOMAS A. HOOVER.
